UNITED STATES PATENT OFFICE

JAMES E. ECKERSLEY, OF ABERDEEN, WASHINGTON, ASSIGNOR OF ONE-HALF TO ALEXANDER POLSON, OF HOQUIAM, WASHINGTON

FEED-ROLL MECHANISM FOR VENEER AND SHINGLE MACHINES

Application filed August 20, 1929. Serial No. 337,162.

This invention is an improvement on the feed roll mechanism shown in my Patent No. 1,552,985 of September 8, 1925, wherein the point of suspension of the pressure bars is to the rear of the longitudinal axis of the feed rollers.

The object of my invention is to suspend the pressure bars above and preferably in front of the longitudinal axis of the feed

10 rollers.

A further object of my invention is to provide the pressure bars with removable block engaging shoes.

15 A further object of my invention is to provide means for limiting the rearward and forward movement of the pressure bars; and with these and other objects in view my invention consists of the parts and combination of parts as will be hereinafter pointed 20 out.

In the drawings:

Figure 1 is a top plan view of the portion of a shingle veneer machine embodying my invention.

25 Figure 2 is an enlarged detail view on the line 2—2, Figure 1, looking in the direction of the arrows.

The reference numeral 1 designates a bed plate having an opening 2 therethrough 30 through which the block of wood operated upon may be fed to the knife of the machine. A frame 4 is mounted on the bed plate on which is mounted the feed rolls and pressure bars as more fully described in my patent 35 above noted, although it is to be noted that I do not confine myself in this case to the structure of bed plate feed roller frame and pressure bars shown in said patent.

I have found in all instances that with the 40 pressure bars pivoted at a point back of the longitudinal axis of the feed rolls that there is some interference between the knife and the pressure bars, and one of the objects of the present invention is to entirely eliminate this 45 possibility as I will now explain.

The feed roll yoke 4 is mounted on the bed plate 1; the feed rolls 6 are suitably journaled to the yoke 4. A series of arms 7 extend forwardly from the yoke 4 and terminate 50 at their forward ends at a point above and

in front of the vertical plane of the longitudinal axis of the feed rolls 6, as clearly shown in the drawings.

Pressure bars 8, arcuate in shape, are pivoted at their upper ends to the forward ends of the arms 7 so that their point of suspension is above and in front of the longitudinal axis of the feed rolls so that when the pressure bars are moved backwards at their lower ends they swing in an arc that never intersects the plane of the knife, thus entirely eliminating all possibility of interference between the knife and pressure bars. The lower end of the pressure bars each have a recess 9 into which hardened steel shoes 10 are removably secured in any suitable manner, said shoes being provided with teeth 11 on their forward edge for penetrating the wood block and hold it securely during the cutting operation. The shoes being removably secured may be readily replaced when necessary without replacing the entire pressure bar.

The yoke 4 and the pressure bars each have a stud 12 on which the ends of the springs 13 are seated, said springs 13 exerting pressure on the pressure bars 8, as will be readily understood.

I have simplified the means for holding the pressure bars to a limited forward position, as I will now explain. A bolt 14 is threaded into the plate 15 cast with the yoke and locked in proper position by a jam nut 16. The forward end of the bolt 14 is positioned in an elongated slot 17 formed in a lug 18 on the pressure bar, the head 19 of the bolt having a sliding engagement with one face of the lug 18, so that the pressure bars are free to be moved on their pivot 20, and in order to limit the rearward movement of the pressure bars I mount an adjustment bolt 21 on the arms 7 to function as a positive stop to limit the rearward movement of the pressure bars, the top of the lug 18 coming into contact with the end of the stop 21. This stop 21 is provided with a jam nut 22. The pressure bars are shown in their extreme rearward movement in dotted lines and are swung to this position by the pressure on the spalts endwise. The pressure bars in moving backward, as above stated, do not interfere with the

knife, nor do they engage the feed rolls at any point in their movement.

The concave surface 23 on the pressure bar is for the purpose of guiding the blocks operated upon from the feeding rollers to the teeth on the shoe 10.

The pivot point 20 of the pressure bars in front of the longitudinal axis of the feed rolls may be varied according to the views of the manufacturer.

What I claim is:

1. In a machine of the kind described, a bed plate having an opening therethrough to receive a block to be operated upon, means for feeding the block through said opening, to a cutter, spalt bars pivotally mounted above and in front of the vertical plane of the longitudinal axis of the block feeding means.

2. In a machine of the kind described, a bed plate having an opening therethrough to receive a block to be operated upon, means for feeding the block through said opening to a cutter, spalt bars pivotally mounted above and in front of the vertical plane of the longitudinal axis of the block feeding means, means on the yoke for limiting the forward movement of said bars, and tension means for holding the bars against the block.

3. In a machine of the kind described, a bed plate having an opening therethrough to receive a block to be operated upon, means for feeding the block through said opening to a cutter, a yoke on said bed plate, spalt or pressure bars pivotally connected to said yoke above and in front of the vertical plane of the longitudinal axis of the feeding means.

4. In a machine of the kind described, a bed plate having an opening therethrough to receive a block to be operated upon, means for feeding the block through said opening to a cutter, a yoke on said bed plate, spalt or pressure bars pivotally connected to said yoke above and in front of the vertical plane of the longitudinal axis of the feeding means, means on the yoke to limit the movement of the bars.

5. In a machine of the kind described, a bed plate having an opening therethrough to receive a block to be operated upon, means for feeding the block through said opening to a cutter, a yoke on said bed plate, spalt or pressure bars pivotally connected to said yoke above and in front of the vertical plane of the longitudinal axis of the feeding means, and tension means connected with the yoke and bar for holding the bar against the block.

6. In a machine of the kind described, a bed plate having an opening therethrough to receive a block to be operated upon, means for feeding the block through said opening to a cutter, a yoke on said bed plate, spalt or pressure bars pivotally connected to said yoke above and in front of the vertical plane of the longitudinal axis of the feeding means, and

adjustable means on the arm to determine the rearward movement of the bar.

7. In a machine of the kind described, means for feeding a block to a cutter, a yoke mounted on the machine, spalt or pressure bars pivotally mounted on said yoke above and in front of the vertical plane of the longitudinal axis of the feeding means, a pin and slot connection between the yoke and bars intermediate the ends of the bars, an adjustable means for limiting the movement of the bars, and tension means connected with the yoke and bars for holding the bars against a block.

In testimony whereof I affix my signature.

JAMES E. ECKERSLEY.
